SEPARATION OF OIL-WAX MIXTURES

Ivan M. Perkins, Brookline, and Stewart S. Kurtz,
Jr., Merion, Pa., assignors to The Atlantic
Refining Company, Philadelphia, Pa., a cor-
poration of Pennsylvania

Application July 3, 1931, Serial No. 548,674

6 Claims. (Cl. 196—20)

The present invention relates to the separation of a mixture of wax and hydrocarbon oil into its respective solid and liquid components, and more particularly to the treatment of that type of oil-wax mixture which is adapted to be separated into such components by the well known process of sweating.

Typical of those oil-wax mixtures which are adapted to be subjected to a process of sweating and therefore adapted to be treated by our process, is the wax cake, commonly known as slack wax, which remains in the filter press when petroleum fractions, such as those known as paraffin distillates, are subjected to a pressing operation. Such oil-wax mixtures usually contain less than 50% of oil.

As is well recognized, sweating processes require prolonged periods of time, large and cumbersome apparatus, and the utilization of considerable heat. An object of the present invention, which is based upon an entirely different principle from that upon which sweating is based, is to replace sweating, thereby to overcome, among others, the objections above stated. By our process, oil-wax mixtures of the type aforesaid may be separated efficiently, economically and rapidly into their respective solid and liquid components. Furthermore, our process and apparatus are capable of separating a composite wax mixture into a series of wax fractions of progressively higher melting points.

If an oil-wax mixture is completely liquefied, then maintained in a static condition and cooled, those components thereof which become solid as a result of the cooling, form as one large mass or cake which occludes substantial quantities of those components which under prevailing conditions are still liquid; the solid components, in forming, apparently becoming so interwoven as to prevent substantial movement of the liquid components occluded therein. It is well known that if such a solid mass is comminuted, it will become of a more or less liquid consistency, presumably because the occluded liquid components are then free to move. The present invention, however, is not based upon nor does it include any step of comminuting a previously solidified oil-wax mixture.

According to our invention, the oil-wax mixture is first raised to a temperature sufficient to completely liquefy the solid portion thereof; thereupon the mixture in a completely liquid state is uniformly cooled to a temperature at which at least a portion thereof will solidify, while simultaneously and continuously, during such cooling

operation, thoroughly agitating the mixture. This procedure, which in each case is properly regulated to the particular oil-wax mixture being treated, results in the formation of distinct agglomerates, each of which may be the size of grains of rice, or of that order, or somewhat larger, for example, of the size of peas. Such agglomerates may then be readily separated from that portion of the mixture which remains liquid, by any suitable method adapted to the separation of solids from liquids, as for example, by draining the liquids from the solids. We have found that agglomerates so formed entrain or occlude very little, if any, of that portion of the mixture which remains liquid during their formation. By treating the agglomerates so formed one or more times, for example, under successively higher temperature conditions, a series of solids of progressively higher melting points may be produced. Thus by our process a substantially oil-free wax may be produced and/or there may be effected a fractional separation of the solid components of an oil-wax mixture into two or more fractions of different melting points.

Hereinafter, for convenience, the term "wax" will be used to indicate that material which forms as a solid during the agglomerating step of our process, and the term "oil" will be used to indicate that material which remains liquid during and immediately after such step. It is to be understood, however, that in some cases, depending upon the particular operating conditions and/or the materials or mixture being treated, what may be called "oil" herein, in fact may be a liquid wax.

A preferred form of our apparatus for carrying out the process consists in a conduit horizontally mounted having an overflow pipe at one end and communicating with a supply tank located adjacent the opposite end so that the liquefied oil-wax mixture to be separated may be introduced into the conduit. Our apparatus in its preferred form also has chambers disposed beneath each end of the conduit. The chamber below the outlet end of the conduit has an opening for admitting cooling liquid thereto. The chamber at its opposite end has at least one, and usually, two outlets for conducting the cooling liquid from the conduit. The conduit is provided with agitating means for maintaining the oil-wax mixture and the cooling liquid in intimate contact during countercurrent passage therethrough.

The primary factors upon which the success of the process depends are: (1) control of the temperature during the cooling step of our process; (2) the rate of agitation during the cooling step;

(3) the detergent characteristics of the cooling liquid; and (4) the difference in specific gravity between the cooling liquid and the liquid oil-wax mixture. The optimum rate of cooling and degree of agitation may vary depending upon the particular oil-wax mixture being treated. A given oil-wax mixture, if cooled too rapidly or shock-chilled, may not produce the desired solid agglomerates. The usual effect of cooling too rapidly or shock-chilling the oil-wax mixture is the formation of that portion thereof which becomes solid into a fibrous mass quite unlike the distinct agglomerates formed by our process which may be easily separated from the portion of the mixture which remains liquid. Cooling too slowly causes that portion which solidifies to form as very small particles from which the liquid portion is difficultly removable. While the particular specific gravity of the cooling liquid is not a significant factor in causing agglomerates of a certain size to form, yet it is a factor of importance in operation; that is, the greater the difference in specific gravity between the cooling liquid and the oil-wax mixture being treated, the more complete will be the separation between the liquid and the mixture.

As regards agitation, if the mixture is agitated too slowly during the cooling step, the desired formation of agglomerates does not occur, but, on the other hand, that portion which becomes solid forms as a mass in which substantial quantities of the portion which remains liquid are occluded; whereas when the mixture is too vigorously agitated during the cooling operation the desired agglomeration is not effected, since the solids form as minute particles from which it is difficult to separate that portion of the mixture which remains liquid. Agitation in accordance with our process is such as to cause that portion of the mixture which becomes solid during our agglomerating step to form as distinct aggregates or agglomerates of the size of grains of rice, or of that order, or even larger, as for example, of the size of peas. Herein, and in the appended claims, the term "thorough" as applied to agitation will be used to indicate an intensity of agitation sufficient to cause this desired formation of agglomerates.

The preferred form of the apparatus herein described is an improvement over vertical type crystallizers disclosed in a copending application filed jointly by one of the present applicants and another inventor. It was found that with certain oil-wax mixtures treated in the vertical type crystallizer there was a tendency for the cooled solidified particles to settle from the top of the crystallizer. This in some cases necessitated a vigorous agitation which led to emulsion troubles. By passing such oil-wax mixtures through the preferred modification of our apparatus herein disclosed, the cooling liquid is passed horizontally in countercurrent direct heat exchange contact with the oil-wax mixture with proper agitation. The immiscible cooling liquid, being heavier than the oil-wax mixture settles therefrom when allowed to stand, but such liquid is kept in intimate contact with the oil-wax mixture during passage through the central portion of the conduit by means of agitating blades affixed to a rotatable shaft. It is found that in the separation of an oil-wax mixture into its components, emulsion troubles are eliminated by employment of our invention.

In some cases, especially where the difference in specific gravity between the oil-wax mixture

and the cooling liquid is small, it may be desirable to elevate the end of the conduit at which the treated oil-wax mixture overflows, thereby to effect a better separation between the oil-wax mixture and the cooling liquid. An elevation of about 10° is in many cases desirable. However, any suitable angle of elevation to the horizontal is within the spirit and contemplation of this invention.

Wax leaving the conduit may be separated from the accompanying oil and small amounts of cooling liquid by draining, spraying with water or a detergent liquid, or by immersing the wax in a liquid and removing it therefrom by screening means.

While the wax products which result from operation of our invention have a substantially higher melting point than the respective oil-wax mixtures from which they are produced, it is possible to rerun these wax products several times to obtain waxes of increasingly higher melting points. In each case, it is preferred to reduce the temperature of the molten oil-wax mixture in the conduits to at least 10° F. below the melting point of the original mixture. Too great a reduction in temperature causes solidification to an undesirable extent of the higher melting constituents; but we have found that it is possible to obtain good results with a reduction of, for example, about 25° F. below the melting point of the oil-wax mixture being treated.

For a better understanding of our invention, reference is had to the accompanying drawing which represents an elevational view, partly in section, of a preferred form of our apparatus.

In the drawing, 1 represents a crystallizer comprising a horizontal conduit 2 having a downwardly extending end chamber 3 connected therewith at the feed end of the crystallizer. The crystallizer may have a downwardly extending chamber 4 at the opposite or wax outlet end of the crystallizer into which chamber cooling fluid may be admitted. A shaft 5 is longitudinally mounted within the conduit 2 and has agitating blades 6 rigidly affixed thereto, and extending to a point adjacent the inner surface of the conduit. One end of the agitator shaft is journaled in the wall above end chamber 4 in bearing 7; while the other end of the shaft extends through the wall above end chamber 3 at point 8, and is driven by any suitable means through gear 9.

Molten oil-wax from supply tank 10 is transferred through line 10a into the feed end of the crystallizer at a suitable rate of flow, controlled by valve 10b in line 10a, and passes through the crystallizer toward overflow spout or trough 16; such passage is assisted, if desired, by adjusting certain of the agitator blades 6 to get a pushing effect toward the outlet end of conduit 2.

A cooling liquid, which, for example, may be a sodium silicate solution, is pumped from tank 11 by pump P and is transferred through pipe 12 controlled by valve 12' into the lower part of end chamber 4 (or in the absence of end chamber 4, into the lower part of the conduit 2 at the outlet end); prior to the introduction into the chamber or conduit the liquid is reduced to the desired temperature by passage through cooler C. Upon reaching the lower level of conduit 2, the cooling liquid flows by gravity toward end chamber 3 in countercurrent direct heat exchange contact with the molten oil-wax mixture and finally settles into end chamber 3.

Pipe 13 controlled by valve 13' taps the cooling liquid from the lower portion of end-chamber 3.

and connects with line 13a controlled by valve 13b which transfers the liquid by gravity back into tank 11. Flow of cooling liquid through the crystallizer is thereby made circuitous.

5 The flow of cooling liquid may be effectively controlled by replacing or supplementing pipe 13 by an adjustable overflow pipe 14 connected to the lower portion of chamber 3, and emptying into the open end of pipe 15 which is connected 10 to line 13a, which in turn is connected to tank 11. Overflow spout 16 secured to the upper portion of conduit 2 above chamber 4, transfers any liquid above the level of its bottom to a suitable washing or separating device 21.

15 In operation, the crystallizer is filled with molten oil-wax at a temperature, for instance, of 125° F., almost to the level of the bottom of the overflow spout 16. Rotation of agitator shaft 5 is then commenced, and the rate of rotation is 20 increased to substantially 60 R. P. M., for example. While the molten oil-wax is agitated, pre-cooled silicate solution at a temperature slightly lower than that to which it is desired to reduce the oil-wax mixture is pumped into end chamber 4, as described heretofore, and upon rising 25 above the bottom of the conduit 2, flows by gravity toward end chamber 3. Agitator blades 6 extend almost to the bottom of conduit 2, and in rotating intimately intermix the molten oil-wax and the 30 cooling solution, thereby providing a thorough heat exchange contact; thus it may be said that the oil-wax and the cooling solution flow in a homogeneous, uniformly disseminated condition countercurrent to each other. When the oil-wax mixture arrives at the finish end, i. e., the 35 end above chamber 4 of the crystallizer, it is at the desired temperature, for instance, about 80° F. when a wax having a melting point of 110° F. is being produced, and overflows through the 40 spout 16. At the same time molten oil-wax mixture from supply tank 10 is continuously fed into the crystallizer above end chamber 3 at a suitable rate. As this molten oil-wax progresses toward the finish end of the crystallizer in intimate contact with and countercurrent to the cooling liquid, 45 its temperature is slowly and evenly reduced to a temperature at which at least a portion of the wax solidifies. The wax content solidifies as small particles, probably crystalline, and the 50 thorough agitation afforded by agitating blades 7 causes the small particles to agglomerate into compact wax masses which are substantially free from oil. Upon reaching the finish end of the crystallizer, substantially all of the wax which 55 solidifies at the reduced temperature is agglomerated.

If the agitation is too slow, agglomeration does not occur. On the other hand, extremely vigorous agitation seems to have a tearing action 60 which prevents or materially hinders agglomeration. Regulation of the rate of agitation makes it possible to control, within limits, the size of agglomerates. Rate of agitation and rate and extent of temperature reduction may be adjusted 65 to suit particular operating conditions. There being no agitation in the lower part of end chamber 3, the mixture of oil-wax and cooling fluid rapidly separates to form a more or less definite interface with the oil-wax, the heavier cooling fluid settling to the bottom of the chamber. Adjustment of the height of the point of discharge 70 of the overflow pipe 14 determines the level of this interface, a desirable level being an inch or so below the bottom of the conduit 2. The cooling fluid which separates into the lower part of

end chamber 3 has, due to its contact with the molten oil-wax, been increased in temperature, for example, to 102° F. By constant addition of molten oil-wax and cooling fluid, and by suitable adjustment of the overflow pipe 14, the ratio of oil-wax to cooling fluid is maintained, and cooling fluid continuously flows from chamber 3 through pipe 14 and treated wax is continuously discharged from conduit 2 through overflow spout 16. A certain amount of cooling fluid is 10 passed out through spout 16 with the treated wax to make its separation from adhering oil easier, the amount of fluid so overflowing being adjustable by regulation of the agitation adjacent the 15 overflow spout.

In accordance with the separating device shown herewith by way of illustration, the overflow mixture passing from spout 16 enters onto endless perforated belt 20 which is mounted within the separating vessel 21. The belt is 20 driven in a clock-wise direction by rollers 22 and 23 within the separator vessel 21, which rollers are in turn driven by any suitable means, not shown; and near the forward end of the path of travel of the endless belt, is mounted partition 24 which divides the vessel 21 into an oil compartment 25, and a wax compartment 26. As the overflow mixture travels with the endless belt, the liquid portions thereof, i. e., the oil and cooling fluid, gravitate through the perforations in 30 belt 20 into oil compartment 25. To assist in a thorough separation of the liquid portions from the wax, the overflow mixture is sprayed with washing liquid in a cooled condition from perforated pipe 27 which is mounted above the endless belt 20. Pipe 27 is supplied with washing liquid from tank 11 through pipe 28 controlled by valve 28', by means of pump P'. It is necessary to keep the temperature of the overflow mixture sufficiently low so that the agglomerated wax content thereof will not melt while passing along the belt 20. Cooler C' surrounding a portion of pipe 28 is employed to reduce the temperature of the washing liquid to the desired extent before the latter is sprayed onto the overflow mixture 40 on belt 20. The washing liquid and cooling fluid may be the same material to assist in the subsequent separation of oil therefrom.

The liquid portions of the overflow mixture and the washing liquid gravitate into compartment 25 and separate therein into a homogeneous lower layer containing the cooling and washing fluids and an upper oil layer. The former is tapped from the bottom of the compartment and returned to tank 11 by pipe 29 controlled by valve 35 45 29', while the supernatant oil layer is drawn off through pipe 30 controlled by valve 30'.

Agglomerated wax passed into compartment 26 from the forward end of the path of travel of the endless belt 20 may be melted by steam, and coil 31 for passage of steam is provided for such purpose. The molten wax may then be drawn off to storage; or in case it is not desired to melt the wax pellets, they may, for example, be received onto a vibrating screen, not shown, and after 55 sufficient drying, be collected as such. Again, the pellets may be collected from compartment 26, carried out through a solution of stearic acid or similar hardening material, and run over a vibrating screen, whereby the wax is left as hard globular pellets.

The following examples will more fully illustrate our process.

Example 1.—A slack wax melting at 105° F. was heated to 125° F. and run through a horizontal 75

crystallizer of the type above described. A 2% solution of sodium silicate in water was passed into the finish end of the crystallizer at 80° F., and drawn from the feed end at 104° F. The oppositely flowing slack wax and silicate solution were thoroughly agitated while in mutual contact in the crystallizer, and as a result, a mixture containing molten oil, agglomerated wax and a certain amount of silicate solution overflowed from the crystallizer at a temperature of 82° F. After draining and spraying this overflow mixture, a wax product was obtained having a melting point of 112.2° F., representing 69% of the original slack wax.

Example 2.—The wax product obtained in Example 1 was heated to 130° F., and passed through the horizontal crystallizer. Its temperature at the overflow end of the crystallizer was reduced to 100° F. The agglomerated wax was freed from the liquid constituents of the charge and from the silicate solution which had overflowed from the crystallizer, and was found to have a melting point of 119° F. This product represented 59% of the charge.

Example 3.—A slack wax melting at 104.5° F. was treated as in Example 1, and a wax product melting at 110° F. was obtained, which represented a 62% yield. On rerunning as in Example 2, a wax product melting at 125° F., and representing 36% of the charge was produced.

By operation of the horizontal, or inclined crystallizer in accordance with our invention, wax particles may be produced which are harder and more free from oil than wax particles resulting from treatment of a similar crude wax in a vertical type crystallizer. This additional hardness and freeness from oil is significant in putting out a wax in the form of rice, which will not stick together at ordinary temperatures. Also, the wax produced in accordance with our invention is more easily and completely freed of adhering oil which is an advantage regardless of the form in which the wax is finished.

The rate of rotation of the agitating blades may be controlled solely on the basis of its effect upon the size of agglomerates, and need not be rotated more rapidly to prevent settling of the wax as is sometimes necessary when a vertical type crystallizer is employed.

What we claim is:

1. A process for separating the higher melting constituents from an oil-wax mixture which is adapted to be sweated, which comprises melting the oil-wax mixture, contacting an approximately horizontally traveling body of the molten oil-wax mixture with a countercurrent body of cooling liquid substantially immiscible with the oil constituent of the mixture and of a specific gravity sufficiently different so that it readily stratifies, whereby the molten mixture is cooled to a temperature at which at least a portion of the wax content thereof crystallizes, thoroughly agitating said mixture while cooling, whereby the crystallized wax combines to form a plurality of agglomerated wax masses, and separating said agglomerated wax masses from the liquid oil.

2. A process for separating the higher melting constituents from an oil-wax mixture which is adapted to be sweated, which comprises melting the oil-wax mixture, intermingling an approximately horizontally traveling stream of said molten oil-wax mixture with a countercurrent stream of a cooling liquid immiscible with said oil-wax mixture and having a different specific gravity therefrom, whereby said molten oil-wax mix-

ture is cooled to a temperature at which at least a portion of the higher melting constituents thereof crystallize, thoroughly agitating the oil-wax mixture during cooling, whereby the crystallized higher melting constituents combine into a plurality of agglomerates, and separating said agglomerates from the constituents of the oil-wax mixture which remain liquid and from the cooling liquid.

3. A process for separating the higher melting constituents from an oil-wax mixture which is adapted to be sweated, which comprises passing a horizontally traveling body of molten oil-wax mixture in countercurrent heat exchange direct contact with a cooling liquid substantially immiscible with said oil-wax mixture and having a different specific gravity therefrom, whereby said oil-wax mixture is cooled to a temperature at which at least a portion of the higher melting constituents thereof crystallize, agitating said oil-wax mixture while cooling to cause said crystallized constituents to combine into a plurality of agglomerates, and separating said agglomerates from the constituents of the oil-wax mixture which remain liquid and from said cooling liquid.

4. A process for separating the higher melting constituents from an oil-wax mixture which is adapted to be sweated, which comprises passing a continuous substantially horizontally traveling stream of molten oil-wax mixture in countercurrent heat exchange direct contact with a cooling liquid immiscible with said oil-wax mixture and having a different specific gravity therefrom, to slowly cool said molten oil-wax mixture to a temperature at least between 10° and 25° F. below the melting point thereof, whereby at least a portion of the higher melting constituents of the oil-wax mixture crystallize, thoroughly agitating the oil-wax mixture while cooling, whereby the crystallized constituents combine to form a plurality of agglomerates, and separating said agglomerates from the constituents of the oil-wax mixture which remain liquid and from the cooling liquid.

5. A process for separating the higher melting constituents from an oil-wax mixture which is adapted to be sweated, which comprises progressively cooling a horizontally traveling body of molten oil-wax mixture by direct contact with a cooling liquid having a progressively lower temperature, thereby reducing the temperature of said molten oil-wax mixture to a temperature at which at least a portion of the higher melting constituents crystallize, thoroughly agitating said mixture during the cooling step, whereby said crystallized constituents combine to form a plurality of agglomerates, and separating said agglomerates from the constituents of the oil-wax mixture which remain liquid and from said cooling liquid.

6. The process for separating the higher melting constituents from an oil-wax mixture which is adapted to be sweated, which comprises passing an approximately horizontally traveling stream of molten oil-wax mixture through an elongated zone in direct countercurrent heat-exchange contact with a cooling liquid, immiscible with and of a higher specific gravity than said oil-wax mixture, whereby the molten oil-wax mixture is cooled to a temperature at which at least a portion of the higher melting constituents thereof crystallize, thoroughly agitating the oil-wax mixture while cooling and passing through said zone, whereby the crystallized constituents combine into a plurality of agglomer-

ates, allowing the cooling fluid and occluded oil to flow into a second zone, said second zone communicating with the end of the elongated zone adjacent the point at which molten oil-wax mixture is introduced thereinto, and being located at a lower level than the said elongated zone and being substantially free from agitation, whereupon the said cooling fluid settles to the bottom of said second zone from which it is removed, and oil gradually rises and again is drawn into said elongated zone, withdrawing oil and wax agglomerates from the opposite end of said elongated zone, and separating said agglomerates from the constituents of the oil-wax mixture 5 which remain liquid.
